UNITED STATES PATENT OFFICE.

LUDA CIZEK, OF DETROIT, MICHIGAN.

NON-CAPSIZING LIFEBOAT.

1,326,575.

Specification of Letters Patent. Patented Dec. 30, 1919.

Application filed May 22, 1919. Serial No. 298,911.

To all whom it may concern:

Be it known that I, LUDA CIZEK, a citizen of Czecho-Slovakia, residing at Detroit, in the county of Wayne and State of Michigan, 5 have invented certain new and useful Improvements in Non-Capsizing Lifeboats, of which the following is a specification.

The primary object of the invention is the provision of a life boat simple in construction and light in weight readily mounted upon the deck of a vessel for easy launching upon the water whenever desired, simultaneously operable outrigger and keel members being provided for the boat, preventing 15 the same from tipping and capsizing when in use.

A further object of the invention is to provide a life boat with outrigger and keel members adapted for positioning substantially out of the way when the boat is not in use and for ready adjustment to their operative positions when the boat is placed in the water.

A still further object of the invention is 25 to provide adjustable outrigger and keel members connected together for assuming their operative positions when desired, automatic means being provided for maintaining the same in position for use, the structure being simple and easy and inexpensive to manufacture, as well as providing oil-dispensing means when found desirable.

With these general objects in view, the invention consists in the novel combination and arrangement of parts hereinafter 35 fully described, in connection with the accompanying drawings and in which like reference characters designate corresponding parts throughout the several views.

40 In the drawings,

Figure 1 is a top plan view of my invention,

Fig. 2 is a vertical transverse sectional view thereof,

45 Fig. 3 is an enlarged vertical sectional view through one half of the boat with the outrigger shown folded, and the adjacent keel member indicated by dotted lines, the position of both keel members being 50 indicated in their connected open positions,

Fig. 4 is a fragmentary longitudinal sectional view thereof,

55 Fig. 5 is an enlarged horizontal sectional view showing one of the outrigger connectors;

Fig. 6 is an enlarged detail view of the hinge lock employed vertical and

Fig. 7 is a transverse sectional view taken upon line VII—VII of Fig. 6.

Referring more in detail to the drawings, 60 my invention comprises a boat having a hull 10 similar in shape to a canoe, longitudinal recesses 11 in the opposite sides thereof being adapted for the reception of elongated outriggers or floats 12 at the opposite sides 65 of the boat.

A plurality of connectors each consisting of two sections 13 and 14 connected by a hinge 15 are provided between each outrigger 12 and the adjacent side portion 16 70 of the hull 10 forming the inner wall of the recess 11. The outer ends of the connector sections 13 are pivoted as at 17 to the adjacent outrigger 12 while the inner ends of the sections 14 are pivoted as at 18, to 75 said walls 16. The hinges 15 are operable for folding the connector sections 13 and 14 upon each other permitting the outrigger 12 to be moved outwardly and inwardly of the adjacent recess 11 while maintaining 80 parallel relations between the outrigger 12 and the inner wall 16 of said receiving recesses.

The folded positions of the sections 13 and 14 with the outrigger 12 in the recess 85 11 is best illustrated in Fig. 4 of the drawings, the spring catch 19 being provided for each hinge 15 whereby the sections 13 and 14 are automatically locked in longitudinal alinement when outstretched. 90

Cords 20 and 21 are connected between the opposite ends of the outriggers 12 and the bow and stern of the hull 10 respectively, a pulling upon said cords 20 and 21 serving to outwardly move the outrigger 95 12 when the same is positioned within its recess 11, such movement being sufficient to permit such other means as a pole or oar to be used for forcing the outrigger 12 to its operative position with the connector 100 sections 13 and 14 open as illustrated in Fig. 1. When in such a position, the cords 20 and 21 will be held in any suitable manner to maintain the outrigger 12 against longitudinal movement. Whenever desired 105 to fold the sections 13 and 14, the catches 19 may be released by means of pins 22 carried thereby.

Adjustable keel sections 23 substantially triangular in cross section are hinged to the 110

central rib or keel 24 of the hull 10, the keel sections being positioned outwardly and disconnected when not in use as indicated by dotted lines in Fig. 3 of the drawing. The outrigger 12 and keel section 23 upon corresponding sides of the hull 10 are connected together by lines or cords 25 to said hull when the life boat is positioned for use upon the deck of a vessel, the members 23 are outstretched beneath the hull 10 as indicated at one side of the hull in Fig. 3 of the drawings, the keel members 23 serving as positioning struts for the hull when not in use. Upon elevating the hull 10 above the deck of the ship, the keel members 23 automatically close into contact with each other, latch 26 upon one keel section automatically engaging a keeper perforation 27 through the other keel section and automatically locking the keel sections together in their operative positions. The subsequent outward movement of the outriggers 12 then brings the lines 25 taut and braces the outriggers 12 by means of their connection with the keel sections 23.

Suitable oil tanks 28 are provided adjacent the gunwale 29 of the hull 10 having conduits 30 communicating with the outlet pipes 31 within the recesses 11, the floating 30 of oil through the members 31 being regulated by valves 32 in the conduits 30. The discharge of oil upon the water at the sides of the hull 10 is designed to render the surface of the water smooth to a desirable extent. Suitable seats 33 are provided in the hull 10 as well as lockers 34 and 35, a floor member 36 being provided adjacent the bottom thereof, with storage space 37 therebeneath.

40 A serviceable life boat is provided readily positioned for use in time of need, the keel and outrigger members rendering the craft substantially non-capsizable, and capable of maintaining an even keel when traveling 45 through rough water.

What I claim as new is:—

1. A life boat comprising a hull having longitudinal recesses in its opposite sides, elongated outriggers, positioned within said 50 recesses when not in use, keel sections centrally hinged to the bottom of the hull and staying lines connected between the outriggers and the adjacent keel sections adapted for taut positioning when the outriggers 55 are outstretched and the keel sections are lowered during the use of the invention.

2. In combination with a hull having side recesses, float outriggers positioned in said recesses when not in use, hinged connections 60 between said outriggers and the adjacent sides of the hull adapted for automatically locking when in their outstretched positions, keel sections connected to the adjacent outriggers hinged to the keel portion of the hull

and automatic locking connections between 65 said keel sections when the keel sections are closed against each other for use.

3. A life boat comprising a hull, keel sections centrally hinged to the bottom of the hull longitudinally thereof adapted for outstretched positioning supportingly beneath 70 the hull when the boat is not in use and latch connections between the hull sections adapted for automatically locking upon the swinging of the keel sections together, in 75 their operative depending position.

4. A life boat comprising a hull, keel sections centrally hinged to the bottom of the hull longitudinally thereof adapted for outstretched positioning supportingly beneath 80 the hull when the boat is not in use, latch connections between the hull sections adapted for automatically locking upon the swinging of the keel sections together, in their operative depending position, outriggers attached longitudinally of the sides of the hull adapted for outward movement to each 85 operative position and stay lines connected between the said outriggers and keel sections.

5. A life boat comprising a hull having longitudinal recesses in the sides thereof, elongated outriggers adapted for seating within said recesses, hinged connectors between said outriggers and the inner walls 95 of said recesses adapted for maintaining the outriggers in parallelism with said walls during the operation of the outriggers, locking means for said connectors adapted for maintaining the connectors outstretched 100 when the outriggers are positioned for use and connecting cords between the ends of the outriggers and the bow and stern portions of the hull.

6. A life boat comprising a hull having 105 longitudinal recesses in the sides thereof, elongated outriggers adapted for seating within the said recesses, hinged connectors between said outriggers and the inner walls 110 of said recesses adapted for maintaining the outriggers in parallelism with said walls during the operation of the outriggers, locking means for said connectors adapted for maintaining the connectors outstretched 115 when the outriggers are positioned for use, connecting cords between the ends of the outriggers and the bow and stern portions 120 of the hull, keel sections hingedly connected centrally of the bottom of the hull adapted for supporting the latter when positioned upon the deck of a vessel, stay lines connected between the outriggers and the adjacent keel sections and automatic means adapted for locking the keel sections together when closed upon each other.

In testimony whereof I affix my signature.

LUDA CIZEK.
